International Search Report and Written Opinion for PCT/US2016/036394 dated Oct. 18, 2016.

Primary Examiner — Christopher Demeree(74) *Attorney, Agent, or Firm* — Womble Bond Dickinson (US) LLP(57) **ABSTRACT**

In one aspect, the disclosure is generally directed to a carton for holding at least one article. The carton comprising a plurality of panels comprising a bottom panel, a front panel foldably connected to the bottom panel, at least one back panel, a top panel, a lid panel foldably connected to the top panel. At least one end flap is foldably connected to a respective panel of the plurality of panels. A base comprises at least the bottom panel, and the front panel. A lid is pivotably attached to the base. The lid comprises the top panel and the lid panel and is movable between a closed position preventing access to the base and an open position allowing access to the base. Locking features are for releasably attaching the lid to the base in the closed position. The locking features comprises at least one male portion in the front panel and at least one female portion in the at least one end flap.

CARTON WITH LOCKING FEATURE

CROSS REFERENCE TO RELATED APPLICATIONS

This application claims the benefit of U.S. Provisional Patent Application No. 62/230,598 filed Jun. 9, 2015.

INCORPORATION BY REFERENCE

The disclosure of U.S. Provisional Patent Application No. 62/230,598, which was filed Jun. 9, 2015, is hereby incorporated by reference for all purposes as if presented herein in its entirety.

BACKGROUND OF THE DISCLOSURE

The present invention generally relates to packages or cartons for holding and dispensing one or more products, such as food products. More specifically, the present disclosure relates to cartons with reclosable locking features.

SUMMARY OF THE DISCLOSURE

In one aspect, the disclosure is generally directed to a carton for holding at least one article. The carton comprising a plurality of panels comprising a bottom panel, a front panel foldably connected to the bottom panel, at least one back panel, a top panel, a lid panel foldably connected to the top panel. At least one end flap is foldably connected to a respective panel of the plurality of panels. A base comprises at least the bottom panel, and the front panel. A lid is pivotably attached to the base. The lid comprises the top panel and the lid panel and is movable between a closed position preventing access to the base and an open position allowing access to the base. Locking features are for releasably attaching the lid to the base in the closed position. The locking features comprises at least one male portion in the front panel and at least one female portion in the at least one end flap.

In another aspect, the disclosure is generally directed to a blank for forming a carton for holding at least one article. The blank comprises a plurality of panels comprising a bottom panel, a front panel foldably connected to the bottom panel, at least one back panel, a top panel, a lid panel foldably connected to the top panel. At least one end flap is foldably connected to a respective panel of the plurality of panels. Base features are for forming a base in the carton formed from the blank. The base features comprising at least the bottom panel, and the front panel. Lid features are for forming a lid in the carton formed from the blank. The lid is pivotably attached to the base. The lid features comprising the top panel and the lid panel. The lid is movable between a closed position preventing access to the base and an open position allowing access to the base. Locking features are for releasably attaching the lid to the base in the closed position. The locking features comprises at least one male portion in the front panel and at least one female portion in the at least one end flap.

In another aspect, the disclosure is generally directed to a method of forming a carton. The method comprises obtaining a blank comprising a plurality of panels comprising a bottom panel, a front panel foldably connected to the bottom panel, at least one back panel, a top panel, a lid panel foldably connected to the top panel. At least one end flap is foldably connected to a respective panel of the plurality of panels. The blank comprising base features, lid features, and

2

locking features. The base features comprise at least the bottom panel, and the front panel. The lid features comprise the top panel and the lid panel. The locking features comprise at least one male portion in the front panel and at least one female portion in the at least one end flap. The method comprises forming the base by positioning the front panel relative to the bottom panel and forming the lid by positioning the lid panel relative to the top panel. The lid is pivotably attached to the base and movable between a closed position preventing access to the base and an open position allowing access to the base. The method comprises releasably attaching the lid to the base in the closed position by engaging the locking features.

Those skilled in the art will appreciate the above stated advantages and other advantages and benefits of various additional embodiments from reading the following detailed description of the embodiments with reference to the below-listed drawing figures.

BRIEF DESCRIPTION OF THE DRAWINGS

According to common practice, the various features of the drawings discussed below are not necessarily drawn to scale. Dimensions of various features and elements in the drawings may be expanded or reduced to more clearly illustrate the embodiments of the disclosure.

FIG. 1 is plan view of exterior surface of a blank according to an embodiment of the present disclosure.

FIG. 1A is a close-up view of a female locking portion according to an embodiment of the present disclosure.

FIG. 1B is a close-up view of a male locking portion according to an embodiment of the present disclosure.

FIG. 2 is a top view of the interior surface of a blank according to an embodiment of the present disclosure.

FIG. 3 is a perspective top view of a partially erected carton according to an embodiment of the present disclosure.

FIG. 4 is perspective top view of a partially erected carton according to an embodiment of the present disclosure.

FIG. 5 is perspective view of a fully erected carton in an open configuration according to an embodiment of the present disclosure.

FIG. 6 is a side view of a fully erected carton in a partially open configuration according to an embodiment of the present disclosure.

FIG. 7 is a front view of a fully erected carton in a partially open configuration according to an embodiment of the present disclosure.

FIG. 8 is a front view of a fully erected carton in a closed configuration according to an embodiment of the present disclosure.

FIG. 9 is perspective view of a first exterior corner of a fully erected carton in a closed configuration according to an embodiment of the present disclosure.

FIG. 10 is perspective view of a second exterior corner of a fully erected carton in a closed configuration according to an embodiment of the present disclosure.

FIG. 11 is perspective view of a first interior corner of a fully erected carton in a closed configuration according to an embodiment of the present disclosure.

FIG. 12 is perspective view of a second interior corner of a fully erected carton in a closed configuration according to an embodiment of the present disclosure.

Corresponding parts are designated by corresponding reference numbers throughout the drawings.

DETAILED DESCRIPTION

The present disclosure relates generally to various aspects of materials, blanks, packages, cartons, constructs, etc., for

holding food items, and methods of making such materials, blanks, packages, cartons, and constructs. Although several different disclosures, aspects, implementations, and embodiments are provided, numerous interrelationships between, combinations thereof, and modifications of the various disclosures, aspects, implementations, and embodiments are contemplated hereby. In this specification, the terms "lower," "bottom," "upper," "top," "front," and "back," or other terms of orientation, indicate orientations determined in relation to fully erected cartons or packages and any such indication of orientations is not intended to limit the scope of the disclosure as the cartons or packages disclosed herein are capable of different orientations than shown and/or described herein.

FIG. 1 shows an exterior surface 10 of a blank 13 for forming a carton 15 (FIGS. 5-9), which may be referred to as a "clamshell" carton. In one embodiment, the carton 15 may be useful for holding one or more food products such as sandwiches (e.g., paninis, bagels, flatbreads, etc.) or one or more nonfood products, or any other suitable article that may be placed in the carton 15 for service to a customer. The products can be contained in additional packaging and then placed in the carton 15. The carton 15 can include various dispensing features and various opening/closing features. The carton 15 has a reclosable lid 135 pivotably attached to a base 133. The lid 135 is movable between a closed position preventing access to the base 133 and an open position allowing access to the base. The lid 135 is that has various locking and engagement features for releasably attaching the lid to the base 133 in the closed position as described below. The carton 15 could be otherwise shaped and arranged and could be used to hold other food products in other environments without departing from the disclosure.

As shown in FIG. 1, the blank 13 has a longitudinal axis L1 extending generally in the direction of the length of the blank and a lateral axis L2 extending generally in the direction of the width of the blank. In one embodiment, the blank 13 comprises a front panel 23, a bottom panel 25, a first back panel 31, a second back panel 32, a top panel 35, and a lid panel 39. The bottom panel 25 is foldably connected to the front panel 23 at a lateral fold line 27, the first back panel 31 is foldably connected to the bottom panel 25 at a lateral fold line 33, the second back panel 32 is foldably connected to the first back panel 31 at a lateral fold line 34, the top panel 35 is foldably connected to the second back panel 32 at a lateral fold line 37, and the lid panel 39 is foldably connected to the top panel 35 at a lateral fold line 41.

In one embodiment, the front panel 23 is foldably connected to a first end flap 45 and a second end flap 47. The bottom panel 25 is foldably connected to a third end flap 49 and a fourth end flap 51. The first back panel 31 is foldably connected to a fifth end flap 53 and a sixth end flap 55. The second back panel 32 is foldably connected to a seventh end flap 57 and an eighth end flap 59. The top panel 35 is foldably connected to a ninth end flap 63 and a tenth end flap 65.

As illustrated in FIG. 1, the end flap 63 is foldably connected to a first attachment flap 69 at an oblique fold line 71 and the end flap 65 is foldably connected to a second attachment flap 73 at an oblique fold line 75. When the carton 15 is erected, the end flaps 45, 49, 53, 57, 63 and attachment flap 69 close the first end 77 of the carton 15, and the end flaps 47, 51, 55, 59, 65 and attachment flap 73 close the second end 79 of the carton 15. Different flaps arrangements can be used for closing the ends 77, 79 of the carton 15. For example, end flaps 49, 51 could be folded inward

after the inward folding of end flaps 45, 47, 53, 55 so that the end flaps 49, 51 are on the exterior of the carton as shown in FIG. 5. Alternatively, the end flaps 45, 47, 53, 55 could be folded after the end flaps 49, 51 so that the end flaps 45, 47, 53, 55 are on the exterior of the carton (not shown).

In the illustrated embodiment, the end flaps 45, 49, 53, 57, 63 extend along a first marginal area of the blank 13 and are foldably connected at a first longitudinal fold line 81 that extends along the length of the blank 13. The end flaps 47, 51, 55, 59, 65 extend along a second marginal area of the blank 13 and are foldably connected at a second longitudinal fold line 83 that also extends along the length of the blank 13. The longitudinal fold lines 81, 83 may be, for example, substantially straight, decoratively curved, or offset at one or more locations to account for the shape of the carton, for blank thickness, or for other factors.

In one embodiment, the first back panel 31 comprises cuts 85 and second back panel 32 comprises cuts 87. As shown in FIG. 1, the cuts 85, 87 are configured in an "X" configuration and define relief portions 91 in the back panels 31, 32. The relief portions 91 prevent the back panels 31, 32 from buckling when the carton is opened or closed. The relief portions 91 could be otherwise shaped, arranged, configured, and/or omitted without departing from the scope of the disclosure.

In one embodiment, the end flaps 49, 51, 63, 65 each comprise a respective outer edge 93a, 93b, 93c, 93d. The edges, 93a, 93b can have a generally concave curved portion 95a, 95b and the edges 93c, 93d can have generally convex curved portion 95c, 95d. The lid panel 39 may comprise an outer edge 93f that is curved and may comprise two convex curved portions 97a, 97b and a concave curved portion 97c connecting the convex curved portions 97a, 97b.

In one embodiment, the front panel 23 comprises an outer edge 93g, and side edges 93h, 93i. In one embodiment, the outer edge 93g may be curved and may comprise two concave curved portions 99a, 99b and a convex curved portion 99c connecting the concave curved portions 99a, 99b. The front panel 23 can have a width "w" that matches the overall depth of the carton such that when the blank 13 is formed into a carton, at least a portion of the outer edge 93g is substantially approximate to or in contact with a portion of the top panel 35.

As shown in FIGS. 1-1B, the blank comprises locking features which include male portions 101a, 101b in the front panel 23 and female portions 103a, 103b in respective end flaps 63, 65. When the carton is formed from the blank, the locking features are generally located in the ends 77, 79 of the carton. The male portions 101a, 101b generally extend or project outward from each of the upper corners 105, 107 of the front panel 23. Each of the female portions 103a, 103b in the end flaps 63, 65 accepts a respective male portions 101a, 101b forming a respective releasable lock 109a, 109b (see FIGS. 9 and 10). As discussed in more detail below, the female portions 103a, 103b include flaps 111a, 111b that are displaced by the male portions 101a, 101b when the lid 135 is positioned in the closed position to create openings 113a, 113b (FIGS. 9 and 10) in the respective end flaps 63, 65.

In one embodiment, the male portions 101a, 101b are projections or tabs that extend outwardly from the side edges 115a, 115b of the front panel 23. The tabs 101a, 101b each respectively include a notch 117a, 117b adjacent the side edges 115a, 115b and a curved portion 119a, 119b (FIG. 7). Each of the notches 117a, 117b and the curved portions 119a, 119b define a lip 121a, 121b (i.e., the portion of the tabs 101a, 101b that engage a portion of the female portions 103a, 103b when carton 15 is positioned in the closed

orientation). The tabs 101a, 101b, the notches 117a, 117b, and the curved portions 119a, 119b could be otherwise shaped, arranged, and/or configured without departing from the scope of the disclosure.

As shown in FIGS. 1 and 1A, the female portions 103a, 103b of the locking features are located a distance "d" from the respective fold lines 81, 83. The first female portion 103a is defined by two longitudinal cuts 123a, 125a generally extending from respective portions of the oblique fold line 71 and a lateral cut 128a extending between the ends of longitudinal cuts 123a, 125a. The second female portion 103b is defined by two longitudinal cuts 123b, 125b generally extending from respective portions of the oblique fold line 75 and a lateral cut 128b extending between the ends of longitudinal cuts 123b, 125b. The cuts 123a, 125a, 128a and 123b, 125b, 128b define the foldable flaps 111a and 111b in the respective end flaps 63, 65. The female portions 103a, 103b, the cuts 123a, 125a, 128a, 123b, 125b, and the flaps 111a, 111b could be otherwise shaped, arranged, and/or configured without departing from the disclosure.

In one exemplary method of forming the blank 13 into the carton 15 having a base 133 and a reclosable lid 135, the blank 13 is first placed with the interior surface 137 facing up as illustrated in FIG. 2. At least one product (not shown) may be placed on the bottom panel 25, alternatively the product may be placed on the bottom panel after the formation of the carton 15. The base 133 of the carton may be formed prior to or after placing the product F on the bottom panel 25, by upwardly folding the front panel 23 and back panel 31 relative to the bottom panel 25 as illustrated in FIG. 3. The end flaps 45, 53 can be folded inwardly and the end flap 49 may be folded upwardly relative to the bottom panel 25. The end flaps 45, 49, 53 can be positioned to at least partially overlap and to at least partially close a first end 77 of the base 133. The end flaps 47, 55 may be folded inwardly and the end flap 51 may be folded upwardly relative to the bottom panel 25, and end flaps 47, 51, 55 can be positioned to at least partially overlap and to at least partially close a second end 79 of the base 133. The reclosable lid 135 can be formed by upwardly folding the second back panel 32 and the end flaps 63, 65 relative to the top panel 35. The end flaps 57, 59 can be positioned on the inside of and can partially overlap the end flaps 63, 65, respectively. The lid panel 39 can be upwardly folded relative to the top panel 35 along lateral fold line 41, and the attachment flaps 69, 73 can be positioned on the inside of and can partially overlap the lid panel 39. Other folding sequences or configurations could be used without departing from the scope of the disclosure. For example, the end flaps 45, 47, 53, 55, 57, 59 and the attachment flaps 69, 73 can be positioned on the exterior of the carton without departing from the scope of this disclosure.

As illustrated in FIG. 5, the reclosable lid 135 comprises the top panel 35, the lid panel 39, the second back panel 32 and the end flaps 63, 65. The reclosable lid 135 is hingedly connected to the first back panel 31 along fold lateral fold line or hinge 34. The reclosable lid 135 is positionable in a closed (first) position wherein the lid panel 39 is positioned to at least partially overlap the front panel 23 and wherein the locking features 101a, 101b, 103a, 103b are engaged, preventing access to the interior of the carton 15. The reclosable lid 135 is positionable in an open (second) position wherein the releasable locks 109a, 109b are disengaged, allowing access to the interior of the carton 15. When the reclosable lid 135 is in the closed position, the locking tabs 101a, 101b extend from the front panel 23 and displace or flex the flaps 111a, 111b outwardly to form the openings

113a, 113b. The flexing of the flaps 111a, 111b provides clearance for receiving the locking tabs 101a, 101b as the lid 135 is closed. As illustrated in FIGS. 9 and 10, each of the openings 113a, 113b has a respective edge 139a, 139b and each tab 101a, 101b may engage the respective openings 111a, 111b and/or the respective edges 139a, 139b to hold the lid 135 in the closed position.

In one exemplary method of opening the carton 15, the front panel 23 is pushed inwardly generally at the center, 10 releasing or disengaging the locking features 101a, 101b, 103a, 103b. The reclosable lid 135 is upwardly lifted and pivots at hinge or fold line 34 to the open position, as 15 illustrated in FIG. 5. The carton 15 may be reclosed by positioning the reclosable lid 135 in the closed position by downwardly folding the lid 186 and pushing down on the top panel 35 such that the flaps 111a, 111b in the end flaps 63, 65 are brought into engagement with the locking tabs 101a, 101b extending from the front panel 23. As the locking tabs 101a, 101b slide past the flaps 111a, 111b and edges 139a, 20 139b an audible click is produced to provide feedback to the user that the locking features of the lid 135 are engaged. The foldable flaps 111a, 111b in the end flaps 63, 65 of the lid 135 also flex outwardly, extending the opening 113a, 113b to provide added space to accommodate the locking tabs 101a, 25 101b without deformation to the audible lock position. Also the flaps 111a, 111b may conceal or hide the locking tabs 101a, 101b for a clean aesthetic look.

In another exemplary method of opening the carton 15, a force may be applied to the lid panel 39. If the lid 135 is 30 attempted to be opened by applying a force near the center of the lid panel 39 (e.g., attempting to lift the lid 135 by grasping near the center of the lid panel 39), the sides of the lid 135 comprising end flaps 63, 65 flex inwardly resulting in outward movement of the locking tabs 101a, 101b 35 through the openings 113a, 113b and displacement of the flaps 111a, 111b, causing more surface area of the locking tabs 101a, 101b to be engaged by the edges 139a, 139b, and causing an increase in the locking force that resists the opening of the lid. However, to open the reclosable lid 135 40 and prevent the locking force increase, the opening force may be applied to any area substantially off center, such as the edges 141a, 141b (FIG. 7) of the lid 135. By applying the opening force off center, the sides of the lid 135 flex outwardly, allowing the notches 117a, 117b and the tabs 101a, 101b to clear the edges 139a, 139b and the flaps 111a 45 and 111b allowing the lid to be raised. Further, an audible click may be produced as the tabs 101a, 101b disengage when the carton 15 is opened.

The carton 15 can be formed, closed, and/or opened by other alternative methods and steps without departing from the disclosure.

In general, the blank may be constructed from paperboard having a caliper so that it is heavier and more rigid than ordinary paper. The blank can also be constructed of other materials, such as cardboard, sheet plastics or any other material having properties suitable for enabling the carton to function at least generally as described above. The blank can be coated with, for example, a clay coating. The clay coating may then be printed over with product, advertising, and other information or images. The blanks may then be coated with a varnish to protect information printed on the blanks. The blanks may also be coated with, for example, a moisture barrier layer, on either or both sides of the blanks. The blanks can also be laminated to or coated with one or more sheet-like materials at selected panels or panel sections.

As an example, a tear line can include: a slit that extends partially into the material along the desired line of weakness,

and/or a series of spaced apart slits that extend partially into and/or completely through the material along the desired line of weakness, or various combinations of these features. As a more specific example, one type of tear line is in the form of a series of spaced apart slits that extend completely through the material, with adjacent slits being spaced apart slightly so that a nick (e.g., a small somewhat bridging-like piece of the material) is defined between the adjacent slits for typically temporarily connecting the material across the tear line. The nicks are broken during tearing along the tear line. The nicks typically are a relatively small percentage of the tear line, and alternatively the nicks can be omitted from or torn in a tear line such that the tear line is a continuous cut line. That is, it is within the scope of the present disclosure for each of the tear lines to be replaced with a continuous slit, or the like. For example, a cut line can be a continuous slit or could be wider than a slit without departing from the present disclosure.

In accordance with the exemplary embodiments, a fold line can be any substantially linear, although not necessarily straight, form of weakening that facilitates folding therealong. More specifically, but not for the purpose of narrowing the scope of the present disclosure, fold lines include: a score line, such as lines formed with a blunt scoring knife, or the like, which creates a crushed or depressed portion in the material along the desired line of weakness; a cut that extends partially into a material along the desired line of weakness, and/or a series of cuts that extend partially into and/or completely through the material along the desired line of weakness; and various combinations of these features. In situations where cutting is used to create a fold line, typically the cutting will not be overly extensive in a manner that might cause a reasonable user to incorrectly consider the fold line to be a tear line.

The above embodiments may be described as having one or more panels adhered together by glue during erection of the carrier embodiments. The term "glue" is intended to encompass all manner of adhesives commonly used to secure carton panels in place, and is not intended to exclude heat, chemical, or frequency bonding techniques.

The foregoing description of the disclosure illustrates and describes various embodiments. As various changes could be made in the above construction without departing from the scope of the disclosure, it is intended that all matter contained in the above description or shown in the accompanying drawings shall be interpreted as illustrative and not in a limiting sense. Furthermore, the scope of the present disclosure covers various modifications, combinations, alterations, etc., of the above-described embodiments. Additionally, the disclosure shows and describes only selected embodiments, but various other combinations, modifications, and environments are within the scope of the disclosure as expressed herein, commensurate with the above teachings, and/or within the skill or knowledge of the relevant art. Furthermore, certain features and characteristics of each embodiment may be selectively interchanged and applied to other illustrated and non-illustrated embodiments of the disclosure.

What is claimed is:

1. A carton for holding at least one article, the carton comprising:
  - a plurality of panels comprising a bottom panel, a front panel foldably connected to the bottom panel, at least one back panel, a top panel, and a lid panel foldably connected to the top panel;

at least one end flap foldably connected to a respective panel of the plurality of panels, the at least one end flap comprises an end flap foldably connected to the top panel;

5 a base comprising at least the bottom panel and the front panel;

a lid pivotably attached to the base, the lid comprising the top panel, the lid panel, and the end flap, the lid is movable between a closed position preventing access to the base and an open position allowing access to the base, wherein the lid panel overlaps the front panel when the lid is in the closed position; and

locking features for releasably attaching the lid to the base in the closed position, the locking features comprising at least one male portion in the front panel and at least one female portion being at least partially formed in the end flap.

2. The carton of claim 1, wherein the at least one male portion comprises a projection extending from an upper corner of the front panel and a notch adjacent the projection.

20 3. The carton of claim 2, wherein the projection comprises a curved edge adjacent the notch, the curved edge engaging a portion of the at least one female portion when the carton is in the closed position.

25 4. The carton of claim 1, wherein the at least one female portion includes at least one cut at least partially forming a locking flap foldably connected to end flap, the locking flap is displaced by the at least one male portion when the carton is in the closed position to create a locking opening in the end flap.

30 5. The carton of claim 4, wherein the at least one cut comprises two longitudinal cuts and a lateral cut extending between a respective end of each of the two longitudinal cuts.

35 6. The carton of claim 1, wherein the lid panel comprises a curved edge comprising a first convex portion, a second convex portion, and a concave portion connecting the first convex portion and the second convex portion.

40 7. The carton of claim 6, wherein the curved edge is a first curved edge and the concave portion is a first concave portion, the front panel comprises a second curved edge comprising a second concave portion, a third concave portion, and a third convex portion connecting the second concave portion and the third concave portion.

45 8. The carton of claim 1, wherein the at least one back panel comprises a first back panel foldably connected to the bottom panel, and a second back panel foldably connected to the first back panel and the top panel, the lid comprising the second back panel and being hingedly connected to the first back panel.

50 9. The carton of claim 1, wherein the end flap is a first end flap, the at least one end flap comprises a second end flap foldably connected to the bottom panel.

10. The carton of claim 9, wherein the first end flap has a concave edge and the second end flap has a convex edge.

55 11. The carton of claim 1, wherein the plurality of panels further comprises an attachment flap foldably connected to the end flap, the attachment flap being in face-to-face contact with the lid panel to attach the end flap to the lid panel and form a corner of the lid.

12. The carton of claim 1, wherein each of the front panel and the lid panel is disposed opposite to the at least one back panel.

60 13. The carton of claim 12, wherein the end flap extends from the at least one back panel to the lid panel.

14. The carton of claim 1, wherein the front panel is foldably connected to the bottom panel along a first fold line,

the end flap is foldably connected to the top panel along a second fold line, and the first fold line and the second fold line are perpendicular to one another.

15. The carton of claim 1, wherein the front panel is foldably connected to the bottom panel along a first lateral fold line, the lid panel is foldably connected to the top panel along a second lateral fold line, and the end flap is foldably connected to the top panel along a longitudinal fold line.

16. The carton of claim 1, wherein the end flap extends from the at least one back panel toward the front panel when the carton is in the closed position.

17. A blank for forming a carton for holding at least one article, the blank comprising:

a plurality of panels comprising a bottom panel, a front panel foldably connected to the bottom panel, at least one back panel, a top panel, and a lid panel foldably connected to the top panel;

15 at least one end flap foldably connected to a respective panel of the plurality of panels, the at least one end flap comprises an end flap foldably connected to the top panel;

20 base features for forming a base in the carton formed from the blank, the base features comprising at least the bottom panel and the front panel;

lid features for forming a lid in the carton formed from the blank, the lid pivotably attached to the base, the lid features comprising the top panel, the lid panel, and the end flap, the lid is movable between a closed position preventing access to the base and an open position allowing access to the base, wherein the lid panel is for overlapping the front panel when the lid is in the closed position; and

locking features for releasably attaching the lid to the base in the closed position, the locking features comprising at least one male portion in the front panel and at least one female portion being at least partially formed in the end flap.

35 18. The blank of claim 17, wherein the at least one male portion comprises a projection extending from an upper corner of the front panel and a notch adjacent the projection.

19. The blank of claim 18, wherein the projection comprises a curved edge adjacent the notch, the curved edge for engaging a portion of the at least one female portion when the carton is in the closed position.

20. The blank of claim 17, wherein the at least one female portion includes at least one cut at least partially forming a locking flap foldably connected to the end flap, the locking flap is displaced by the at least one male portion when the carton is in the closed position to create a locking opening in the end flap.

50 21. The blank of claim 20, wherein the at least one cut comprises two longitudinal cuts and a lateral cut extending between a respective end of each of the two longitudinal cuts.

22. The blank of claim 17, wherein the lid panel comprises a curved edge comprising a first convex portion, a second convex portion, and a concave portion connecting the first convex portion and the second convex portion.

55 23. The blank of claim 22, wherein the curved edge is a first curved edge and the concave portion is a first concave portion, the front panel comprises a second curved edge comprising a second concave portion, a third concave portion, and a third convex portion connecting the second concave portion and the third concave portion.

24. The blank of claim 17, wherein the at least one back panel comprises a first back panel foldably connected to the bottom panel, and a second back panel foldably connected

to the first back panel and the top panel, the lid features comprising the second back panel and the lid is for being hingedly connected to the first back panel, and the base features comprising the first back panel.

5 25. The blank of claim 17, wherein the end flap is a first end flap, the at least one end flap comprises a second end flap foldably connected to the bottom panel.

26. The blank of claim 25, wherein the first end flap has a concave edge and the second end flap has a convex edge.

10 27. The blank of claim 17, wherein the plurality of panels further comprises an attachment flap foldably connected to the end flap, the attachment flap being in face-to-face contact with the lid panel to attach the end flap to the lid panel and form a corner of the lid in the carton formed from the blank.

28. The blank of claim 17, wherein each of the front panel and the lid panel is disposed opposite to the at least one back panel.

29. The blank of claim 28, wherein the end flap extends from the at least one back panel to the lid panel.

30. The blank of claim 17, wherein the front panel is foldably connected to the bottom panel along a first fold line, the end flap is foldably connected to the top panel along a second fold line, and the first fold line and the second fold line are perpendicular to one another.

25 31. The blank of claim 17, wherein the front panel is foldably connected to the bottom panel along a first lateral fold line, the lid panel is foldably connected to the top panel along a second lateral fold line, and the end flap is foldably connected to the top panel along a longitudinal fold line.

30 32. The blank of claim 17, wherein the end flap extends from the at least one back panel toward the front panel when the carton formed from the blank is in the closed position.

33. A method of forming a carton, comprising:

obtaining a blank comprising a plurality of panels comprising a bottom panel, a front panel foldably connected to the bottom panel, at least one back panel, a top panel, and a lid panel foldably connected to the top panel, at least one end flap foldably connected to a respective panel of the plurality of panels, the at least one end flap comprises an end flap foldably connected to the top panel, the blank comprising base features, lid features, and locking features, the base features comprising at least the bottom panel, and the front panel, the lid features comprising the top panel, the lid panel, and the end flap, and locking features comprising at least one male portion in the front panel and at least one female portion at least partially formed in the end flap; forming the base by positioning the front panel relative to the bottom panel;

50 forming the lid by positioning the lid panel relative to the top panel, the lid being pivotably attached to the base and movable between a closed position preventing access to the base and an open position allowing access to the base;

releasably attaching the lid to the base in the closed position by engaging the locking features, wherein the lid panel overlaps the front panel when the lid is in the closed position.

34. The method of claim 33, wherein the at least one male portion comprises a projection extending from an upper corner of the front panel and a notch adjacent the projection and the projection comprises a curved edge adjacent the notch, the releasably attaching comprises engaging the curved edge with a portion of the at least one female portion when the carton is in the closed position.

60 35. The method of claim 33, wherein the at least one female portion includes at least one cut at least partially

11

forming a locking flap foldably connected to the at least one end flap, the releasably attaching the lid to the base comprises displacing the locking flap by the at least one male portion when the carton is in the closed position to create a locking opening in the end flap.

36. The method of claim **35**, wherein the releasably attaching the lid to the base comprises engaging the male portion with an edge of the locking opening.

37. The method of claim **33**, wherein the lid panel comprises a first curved edge comprising a first convex portion, a second convex portion, and a first concave portion connecting the first convex portion and the second convex portion, the front panel comprises a second curved edge comprising a second concave portion, a third concave portion, and a third convex portion connecting the second concave portion and the third concave portion.

38. The method of claim **33**, wherein the at least one back panel comprises a first back panel foldably connected to the bottom panel, and a second back panel foldably connected to the first back panel and the top panel, the lid features comprising the second back panel and the lid is hingedly connected to the first back panel, and the base features comprising the first back panel.

39. The method of claim **38**, wherein the lid is connected to the base at hinge between the first back panel and the second back panel, the releasably attaching the lid to the base comprises pivoting the lid at the hinge from the open position to the closed position.

12

40. The method of claim **33**, wherein the plurality of panels further comprises an attachment flap foldably connected to the end flap, the forming the lid comprises positioning the attachment flap being in face-to-face contact with the lid panel to attach the end flap to the lid panel and form a corner of the lid.

41. The method of claim **33**, further comprising disengaging the locking features and moving the lid from the closed position to the open position.

42. The method of claim **33**, wherein each of the front panel and the lid panel is disposed opposite to the at least one back panel.

43. The method of claim **42**, wherein the end flap extends from the at least one back panel to the lid panel.

44. The method of claim **33**, wherein the front panel is foldably connected to the bottom panel along a first fold line, the end flap is foldably connected to the top panel along a second fold line, and the first fold line and the second fold line are perpendicular to one another.

45. The method of claim **33**, wherein the front panel is foldably connected to the bottom panel along a first lateral fold line, the lid panel is foldably connected to the top panel along a second lateral fold line, and the end flap is foldably connected to the top panel along a longitudinal fold line.

46. The method of claim **33**, wherein the end flap extends from the at least one back panel toward the front panel when the carton is in the closed position.
